US0D1096057S

(12) **United States Design Patent** (10) **Patent No.:** **US D1,096,057 S**
(45) **Date of Patent:** **** Sep. 30, 2025**

(54) **HOLDER AND STAND FOR PAPER GROCERY BAG**

(71) Applicants: **David Barrickman**, Anderson, IN (US); **Gene Schildmeier**, Anderson, IN (US)

(72) Inventors: **David Barrickman**, Anderson, IN (US); **Gene Schildmeier**, Anderson, IN (US)

(**) Term: **15 Years**

(21) Appl. No.: **29/848,291**

(22) Filed: **Aug. 1, 2022**

(51) **LOC (15) Cl.** **06-06**

(52) **U.S. Cl.**

USPC **D6/512; D34/6**

(58) **Field of Classification Search**

USPC D34/1-11; D3/328; D6/512, 513; D9/455

CPC . B65B 67/00; B65B 67/12; B65F 1/00; B65F 1/06; B65F 1/1415; B65F 2001/061

See application file for complete search history.

(57) **CLAIM**

The ornamental design for a holder and stand for paper grocery bag as shown and described.

DESCRIPTION

FIG. 1 is a front perspective view;

FIG. 2 is a front view;

FIG. 3 is a rear view;

FIG. 4 is a left side view;

FIG. 5 is a right side view;

FIG. 6 is a top view;

FIG. 7 is a bottom view.

FIG. 8 is a perspective view showing the holder and stand for grocery bag in condition of use; and,

FIG. 9 is an exploded perspective view thereof.

The broken lines in the drawings depict environment, and form no part of the claimed design.

1 Claim, 9 Drawing Sheets
